INVENTOR:

Henry W. Baltz Sr.

UNITED STATES PATENT OFFICE.

HENRY W. BALTZ, SR., OF PHILADELPHIA, PENNSYLVANIA, ASSIGNOR OF ONE-HALF OF HIS RIGHT TO JOHN C. CLIME, OF SAME PLACE.

TURBINE WATER-WHEEL.

SPECIFICATION forming part of Letters Patent No. 223,979, dated February 3, 1880.

Application filed October 27, 1879.

To all whom it may concern:

Be it known that I, HENRY W. BALTZ, Sr., of Philadelphia, in the county of Philadelphia and State of Pennsylvania, have invented certain new and useful Improvements in Turbine Water-Wheels; and I do hereby declare the following to be a full, clear, and exact description of the invention, such as will enable others skilled in the art to which it pertains to make and use it, reference being had to the accompanying drawing, which forms part of this specification, in which—

Figure 1 is a transverse vertical section.

My invention has reference to an improvement on Letters Patent of the United States No. 214,813, granted to John C. Clime, for turbine water-wheels; and it has for its object the provision of means for obtaining an additional amount of power from the same or required head or flow of water necessary for running wheels constructed according to said patent.

My invention accordingly consists in the provision of a turbine water-wheel placed upon a shaft inclosing a concentric gate provided with chutes, in combination with another or a second turbine wheel secured upon said shaft a short distance below that of the first-named wheel and an intervening fixed chute-ring, whereby the unspent power contained in the water, as the same issues from the first wheel, will be utilized to give additional power to the wheel-shaft by passing said water to and through the second wheel.

Referring to the accompanying drawing, A represents the wheel-case, provided with a lid or cover, a , step-bearing B' for the step b of the shaft B , and a fixed annular chute-ring, E , which is secured in position on a shoulder, a^3 , formed on said case, and is firmly held thereon by means of the screws a' a' , or by other suitable means.

a^2 is a water conduit or pipe conducting the water through the opening a^4 in the center 45 of the lid or cover a to the chamber D' , in which is the annular movable gate D , having chutes d formed therein. Surrounding said gate, and secured to the shaft B , is a turbine water-wheel, C . Said conduit, chamber,

gate, and wheel are such as are described in 50 the patent already referred to, and therefore need no further particular description, only stating that the buckets of said wheel C receive the impact of the water vertically. F is another or a second turbine wheel, firmly secured to shaft B below the chute-ring E , and is formed with buckets f f , so arranged and shaped as to receive the impact of the water 55 horizontally.

The operation is as follows: The shaft d^2 60 being turned, the pinion d' thereon engaging with a rack on the gate D , as shown, the latter is adjusted to allow the required amount of water to pass through its contained chutes d d to the buckets of the wheel C to revolve 65 the same. As the water flows off of said wheel C it falls into the chamber E' upon and passes through the chutes e e of the chute-ring E , striking the buckets f f of the wheel F , thereby imparting force to said wheel F to obtain an 70 additional power from the shaft B , which addition in power will be nearly equal to the amount of unspent power contained in the water falling from the wheel C . This unspent power is very considerable, and means which 75 provide for its utilization add greatly to the capacity of the turbine wheels.

I have demonstrated by actual test that a wheel six inches in diameter, when placed upon the shaft B in the position shown by the wheel 80 C , will, with a given flow of water, raise a weight of twenty-one pounds attached to a rope passing over a ten-and-one-fourth-inch pulley. With two wheels, as C and F , placed upon the same shaft B , the wheel C being six and the 85 wheel F nine inches in diameter, and with the same head or flow of water, they together will raise a weight of thirty-four pounds—a gain of thirteen pounds, or an increase of power equal to over fifty per cent. of that obtained by using 90 only one turbine wheel.

What I claim as my invention is—

1. The case A , gate D , shaft B , in combination with turbine wheels C and F and intervening chute-ring, E , substantially as shown 95 and described.

2. The wheel-case A , having central opening, a^4 , and annular chute-ring E , in combination

with gate D and wheel C, whereby said case is formed with two water-chambers, D' and E', substantially as shown and described.

3. The combination of shaft B, turbine wheels C and F, intervening chute-ring E, and case A, the latter being formed with a shoulder or offset, a^3 , for the reception of said chute-ring E, substantially as shown and described.

In testimony that I claim the foregoing I have hereunto set my hand this 14th day of 10 October, 1879.

HENRY W. BALTZ, SR.
